(57) CLAIM

We claim the ornamental design for a golf club head, as shown and described.

DESCRIPTION

FIG. 1 is a perspective view of a golf club head, as viewed from the bottom and one side, according to one embodiment. FIG. 2 is a front elevation view of a golf club head of FIG. 1.

FIG. 3 is a rear elevation view of the golf club head of FIG. 1.

FIG. 4 is a side elevation view of a toe side of the golf club head of FIG. 1.

FIG. 5 is a side elevation view of a heel side of the golf club head of FIG. 1.

FIG. 6 is a top plan view of the golf club head of FIG. 1.

FIG. 7 is a bottom plan view of the golf club head of FIG. 1.

FIG. 8 is a bottom plan view of the golf club head of FIG. 1, the unclaimed moveable weight being shown in an alternate position.

FIG. 9 is a bottom plan view of the golf club head of FIG. 1, the unclaimed moveable weight being shown in an alternate position.

FIG. 10 is a bottom plan view of the golf club head of FIG. 1, the unclaimed moveable weight being shown in an alternate position; and,

FIG. 11 is a bottom plan view of the golf club head of FIG. 1, the unclaimed moveable weight being shown in an alternate position.

The dashed lines in the drawings are for purposes of illustrating environmental structure as well as portions of the design that form no part of the present claimed design.
